CLAIM

The ornamental design for a dog collar as shown and described.

DESCRIPTION

FIG. 1 is a front perspective view of a dog collar according to the present invention;

FIG. 2 is a rear perspective view of the dog collar;

FIG. 3 is a front view of the dog collar;

FIG. 4 is a rear view of the dog collar;

FIG. 5 is a left side view of the dog collar;

FIG. 6 is a right side view of the dog collar;

FIG. 7 is a top view of the dog collar; and,

FIG. 8 is a bottom view of the dog collar.

The broken lines shown in the drawings represent portions of the dog collar that form no part of the claimed design.

1 Claim, 5 Drawing Sheets
